MACHINE FOR RAMMING FOUNDRY CORES
BY MEANS OF COMPRESSED AIR

Fritz Hansberg, Milan, Italy

Application October 15, 1949, Serial No. 121,485
In Italy June 15, 1949

3 Claims. (Cl. 22—10)

1

The present invention relates to a machine for introducing and tamping casting sand into core moulds in order quickly to obtain the formation of cores to be introduced into the castings.

It is an object of the present invention to provide a machine allowing for rapid preparation of cores of any size and shape, by means of mere valve adjustment. Other advantages of the invention will appear from the following description.

The machine according to the invention is essentially composed of a hollow body adapted to contain the casting sand and provided with one or more discharge mouths for discharging in the direction of a support for core moulds; compressed air is introduced into said hollow body by means of a conduit, which is connected thereto through a valve having a large aperture and being quickly operable, which valve may be preceded by another valve for adjustable throttling, which latter valve has a smaller aperture than the first valve.

The accompanying drawing represents a vertical section of one embodiment of the machine according to the invention.

In the embodiment diagrammatically represented in the drawing, the machine is composed of a hollow standard or column 1, whose inner cavity acts as a compressed air receiver or storage tank. To the standard 1 there is connected by way of the bracket 2, the cylindrical body 3 constituting the said storage tank; the walls of the cavity of the body 3 are lined with a perforated metal liner 4 which forms an annular channel with the cylinder wall.

The lower head 5 of the cylinder 3 comprises a conical part 6 terminated by a central hole forming the seat for a replaceable nozzle 7. Outside the cone 6, the head 5 comprises a chamber 8 open inside by way of a plurality of holes 9 covered by a metal wire gauze or network 10.

The bracket 2 carrying the cylinder 3 is rotatable about the standard 1 and can be locked at the top against a head 11 containing a conduit 12, which is in communication with the cylinder 3 by way of a comparatively wide valve 13, and with the inside of the standard 1 by way of a valve having smaller dimensions 14. Valve 13 is extended to form a frusto-conical guide member 13' which together with the upper conical section 3' of the sand chamber provides an annular channel aligned so as to direct compressed air into the channel between cylinder 3 and liner 4.

The valve 13 is controlled by means of a servomotor whose piston 15 is pushed by the com-

2

pressed air entering through the aperture 16 controlled by a suitable valve not represented in the drawing.

The valve 14 is controlled by means of the hand-wheel screw 17 so that its aperture can be adjusted at any time as needed.

Below the cylinder 3, a bracket 18 fastened to the standard 1 supports a core-mould carrying plate 19, which by way of a stem 20 is integral or rigidly connected with a piston 21, which too is displaceable by means of compressed air so as to lift the core-mould carrying plate 19 against the cylinder 3.

With 22 are indicated packings of elastic material and with 23 is indicated a spring reacting against the piston 15.

Operation of the machine is as follows:

The cylinder 3 is filled with casting sand and then tightly locked under the head 11. On the plate 19 there is fixed, for example by means of a pneumatic clamp of a known type, a core-mould 25 in such a manner that its upper opening is placed below the nozzle 7 and is partly covered by the holes 9. If compressed air is introduced through the opening 16, the piston 15 rises against the reaction of the spring 23 and very rapidly opens the valve 13, whence compressed air enters the cylinder 3 and from the top as well as laterally through the holes of the liner 4 presses the sand contained therein, which, therefore, is forced violently out through the nozzle 7 entering the core-mould and filling it completely until the sand comes in forced contact with the metal grating 10, while excess air escapes through the holes 9 and passing into chamber 8 then discharges to the atmosphere through peripheral holes 9 or through larger ejecting holes 26 that may be provided at any convenient point.

During this operation, the core-mould is held against the inner surface of the head 5 of the plate 19 by the action of compressed air acting against the piston 21; when this compressed air is released, the plate 19 goes down again and the core-mould with the formed core can be easily and quickly removed.

The operation of injecting sand into the core-mould is extremely rapid, so as to deserve being called "ramming shot."

As the cores to be formed may widely vary in size and shape, the rapidity of the ramming shot, viz the convenient rapidity of ramming the sand into the mould so as to obtain the best effect, may vary in accordance with the situation. To this end the valve 14 should be acted upon by means

of the handwheel 17: for comparatively small-sized cores, a moderate opening of the valve 14 will suffice, whilst for larger cores the valve 14 is opened to a larger extent in such a manner that the rapidity of injecting the sand into the core-mould be proportioned to the volume of sand to be injected.

This machine, therefore, may be advantageously used for cores of any shape and size even varying in a wide range, the operation being nevertheless equally rapid and perfect in every case.

Having now particularly described and ascertained the nature of my said invention and in what manner the same is to be performed, I declare that what I claim is:

1. A core blowing machine employing compressed air, comprising in combination a frame structure including a sand chamber having a wide air inlet opening and a narrow sand outlet opening, valve means disposed in said inlet opening for controlling the admission of compressed air into said chamber, valve control means for opening and closing said valve means, and a lining member including a plurality of transverse openings therethrough disposed within said sand chamber spaced apart from the chamber wall and open ended at the side facing the valve means, said valve means including a valve body and a guide member mounted on the side of said valve body facing the said chamber and movable in unison with the valve body, said guide member being shaped and positioned relative to the space between the chamber wall and the lining member so as to direct compressed air into the said space and to provide space for the flow of compressed air into the sand chamber upon opening of said valve means.

2. A core blowing machine employing compressed air, comprising in combination a frame structure including a substantially tubular vertically disposed sand chamber, one end of said chamber forming a narrow nozzle for discharging sand into a core box and the other end a wider air inlet opening for admitting compressed air into the sand chamber, a tubular lining member including a plurality of transverse openings therethrough disposed within said sand chamber concentrically therewith and spaced apart from the wall of the chamber so as to form an annular open channel between the lining member and the chamber wall, and valve means for controlling the rate of flow of compressed air, valve control means for opening and closing said valve means, said valve means including a valve body seated on said inlet opening and a guide member secured to the valve body on the side thereof facing the sand chamber, said guide member being shaped and positioned to direct compressed air into said annular channel and to provide space for the

flow of compressed air into said sand chamber upon opening of said valve means.

3. A core blowing machine employing compressed air, comprising in combination a frame structure including a substantially tubular vertically disposed sand chamber, one end of said chamber forming a narrow nozzle for discharging sand into a core box and the other end a wider air inlet opening for admitting compressed air into the sand chamber, a tubular lining member including transverse openings therethrough disposed within said sand chamber concentrically therewith and spaced apart from the wall of the chamber so as to form an annular open channel between the lining member and the chamber wall, said sand chamber having a substantially frusto-conical section positioned above said lining member, the narrow end of said section including said inlet opening, and valve means for controlling the rate of flow of compressed air through said inlet opening, valve control means opening and closing said valve means, said valve means including a valve body seated on said inlet opening and a guide member secured to the valve body on the side thereof facing the sand chamber and the lining member therein, said guide member having a substantial frusto-conical shape and being positioned within said conical section so as to form a second annular channel therewith, said latter channel being aligned so as to direct compressed air into the annular channel formed by the lining member and the tubular section of the sand chamber upon opening of the valve means, a space being interposed between the adjacent ends of the guide member and the lining member so as to provide for a flow of compressed air leaving said second channel into said tubular section of the sand chamber upon opening of the valve means.

FRITZ HANSBERG.
